UNITED STATES PATENT OFFICE.

JOSEPH MILLOT AND BENOIT MILLOT, OF GRAY, FRANCE.

SPEED-GOVERNOR FOR EXPLOSIVE-ENGINES.

SPECIFICATION forming part of Letters Patent No. 663,183, dated December 4, 1900.

Application filed August 18, 1898. Serial No. 688,857. (No model.)

To all whom it may concern:

Be it known that we, JOSEPH MILLOT and BENOIT MILLOT, citizens of the Republic of France, residing in Gray, Haute - Saône, France, have invented new and useful Improvements in Apparatus for Supplying Oil to Explosion-Engines, which invention is fully set forth in the following specification.

Our invention has for its object an automatic petroleum-feed device applicable to all explosion-motors wherein the cycle comprises a suction period either in the motor-cylinder or in a separate cylinder designed to prepare the explosive mixture.

To form an explosive mixture the combustion of which shall be complete, it is necessary to introduce into the presence of a given quantity of air a determined quantity of petroleum; and it is the object of our invention to provide means for obtaining this result.

In the motors for which our improvement is especially designed (though it is not necessarily limited to any one type) the carburation of the air is effected by drawing petroleum through an exceedingly small orifice (about half a millimeter in diameter) which opens into the tube through which the air flows to the cylinder. It will be easily understood that the petroleum is projected into the tube in quantity which increases with the degree of the partial vacuum created in the tube during the suction-stroke—that is to say, it increases with the tenuity of the air and conversely it is projected very feebly if the air flows in excess. It is clear that the principle of these apparatus is faulty and in complete contradiction to the object desired, as the mode of operation causes the air and petroleum to mix together in an inversely-proportional manner. Their regulation can only be effected within limits which are very restricted and difficult to attain. For this reason petroleum - motors in unskilled hands spread a disagreeable odor, which odor results from the faulty proportions of the air and petroleum admitted to the cylinder, and it is for this reason also that their power has been designated as uncertain.

The apparatus is represented in vertical section in Figure 1. Fig. 2 shows, on a smaller scale, its application to any motor. Fig. 2 is a projection in elevation on a plane per-

pendicular to the plane of section of Fig. 1. We have shown in section in this figure the hereinafter-described centrifugal governor 55 which controls the action of the petroleum-feed device.

In Fig. 2 enough of the motor-engine is shown to enable the application of our invention to be understood, C' being the cylinder, 60 D' the inlet-chamber for the explosive mixture, E' the shaft, and L' L² the passage through which air is drawn in, receiving in its course a charge of petroleum in the intermediate tube or section L.

The oil-supplying apparatus comprises a cylinder A, in which a very light piston B can freely move, the said piston being guided by a central rod C. At its upper part this rod passes through a milled head F, carried by 70 the cover E, said head F adapted to be screwed to thereby vary the distance which separates it from a nut V upon the upper end of the rod. A spring H serves to hold it in any position which it is caused to assume. At its 75 lower part the rod C is formed in two parts of different diameter a and b, the diameter of a being greater than that of b, and these two parts of the rod are separated by a conical portion I, forming a valve which seats upon 80 a socket portion forming the bottom J of the cylinder. A spring K tends to bring the valve to its seat. The end or smaller part b of the rod is formed with a central bore into which open small transverse holes g. A short tube 85 L is formed on the cylinder A and communicates with it through an aperture M. This tube L is provided at its ends with two flanges N N, by means of which the apparatus is interposed in the air-inlet pipe L' L² of the motor-cylinder. A pin-valve P is pressed by a 90 spring R against a hole or passage q, which connects a space r with the said tube L. The rise of this valve is small and is limited by a stop Q. A sheet of fine wire-gauze S is provided, through which the petroleum passes before being utilized in order that it may be freed from any impurities which it may contain. A screwed projection T allows of the reservoir containing petroleum being placed 95 in communication with the apparatus.

A weight B', Fig. 2, is pivoted at O' and turns on the center O in a cylindrical box Z and is operated by gear-wheels X X', the di-

ameters of which are such that the weight B' turns with a velocity half as great as that of the motor. Under the action of centrifugal force the weight B' bears against the concentric fixed surface A' of the box, against which it is shaped to fit exactly, so as to close an orifice z during the suction-stroke of the motor. A spring R' opposes its action to that of the centrifugal force and so long as the normal velocity is not departed from maintains the outer surface of the weight B' at about one millimeter from the said surface A'. The apparatus thus described constitutes a centrifugal governer which according to the variations in speed controls the action of the oil-supplying device.

The operation of the apparatus is as follows: The petroleum, coming from any suitable reservoir, enters the apparatus through the inlet 20 T, passes through the filter S, flows through the central bore formed in the end b of the rod, thence through the holes g therein, so as to fill the space U around the rod, and then stops under the valve I. When the suction- 25 stroke of the motor commences, the draft of air from the cylinder creates in the passage L' L² and short tube L a partial vacuum, which extends through the aperture M therein under the piston B of the apparatus, and as the upper face of the said piston is in communication with the atmosphere by x t the piston is forced downward by the difference of pressure on its two faces and carries with it the rod C, which is fixed thereto. This movement 30 of the piston is limited by the contact of the nut V with the screwed plug F, which is adjustable, as above described. As soon as the rod C commences its movement the valve I thereon leaves its seat and the small holes g 35 therein are closed by the bushing y, in which it slides, and the petroleum contained in the space U around the rod is displaced by the plunger or larger part a of the end of the rod C, rises above the valve I, forces back the pin- 40 valve P, so as to uncover the opening of its hole or passage q, and in a finely-divided condition reaches the air-current which at this moment flows through the short tube or cylinder L, so as to form with it the explosive charge. At 45 the end of the suction-stroke the spring K returns the rod C to its initial position. At each flow of air into the motor-cylinder—that is to say, only when the normal velocity is not exceeded—the apparatus projects into the

short tube L a quantity of petroleum equal 55 to the difference between the cross-sectional areas of the larger and smaller parts a and b of the central rod multiplied by its stroke. When the speed increases, the spring R' of the weight B' yields, and the weight by being 60 applied against the surface A' of the box closes the orifice z therein during the whole of the suction operation. As a consequence of this, the atmospheric pressure being no longer exerted upon the upper face of the 65 piston B, the said piston does not descend and the distribution of petroleum ceases until the normal velocity is resumed.

The piston B can be replaced by a diaphragm of any suitable material connected to the central rod C and producing the same result as the piston.

We claim as our invention the following-defined novel features, substantially as herein-before specified, namely:

1. An oil-feed device for a petroleum-motor, comprising a piston, an oil-admission valve opened by the displacement thereof, one side of said piston communicating with the suction-passage of the motor, and the opposite side communicating with the atmosphere, and a centrifugal governor controlling the latter communication, constructed to close it when the speed becomes excessive, and thereby prevent the displacement of the piston by the suction in said suction-passage.

2. An oil-feed device for a petroleum-motor, comprising a piston, an oil-admission valve opened by the displacement thereof, one side of said piston communicating with the suction-passage of the motor, and the opposite side communicating with the atmosphere through a passage t, a shell A' to which said passage leads, a weighted valve B' revolving in said shell, adapted when thrown outward by excessive speed to close said passage t during the suction-stroke of the engine, and a spring R' adapted to restrain said weight while the speed remains normal.

In testimony whereof we have signed this 100 specification in the presence of two subscribing witnesses.

JOSEPH MILLOT.
BENOIT MILLOT.
